UNITED STATES PATENT OFFICE.

WILLIAM HENRY HARRIS, OF STARK, MONTANA.

AUTOMATIC RAILROAD-SIGNAL.

No. 867,364.

Specification of Letters Patent.

Patented Oct. 1, 1907.

Application filed January 9, 1907. Serial No. 351,497.

To all whom it may concern:

Be it known that I, WILLIAM HENRY HARRIS, a citizen of the United States of America, and a resident of Stark, in the county of Missoula and State of Montana, 5 have invented certain new and useful Improvements in Automatic Railroad-Signals, of which the following is a specification.

The purpose of my invention is to notify the engineer and the train crew as well as the station operators 10 whether a train is on certain parts of the main line which I have divided off into blocks. Also, when the train is side-tracked by means of my automatic signals, the engineer and train crew of an in-coming train are notified, if the switch has been left open. The 15 signal is put into operation by a pliable attachment placed on the forward right hand side above the engineer's cab, which hits against pendulum shaped rods at certain intervals, thus closing an electric circuit for sufficient time to set in operation the signals on 20 the block just entered by the train. As the train passes out of the block, a similar attachment placed on the rear of the train strikes a pendulum and puts out the lights or other indicating device, provided no other train is left on the block running in the same direction. 25 Should there be another train running in the same direction, the danger signal will still be operative by means of my automatic registering device.

With these and other objects in view for enhancing the value of automatic signaling, my invention 30 consists in the novel features of construction hereinafter fully described and concisely claimed.

In order that my invention may be fully understood, I will proceed to describe it with reference to the accompanying drawings, in which:

35 Figure I is a diagrammatic representation of the main line of a railroad being protected by my automatic signals. Fig. II is a side view of my automatic registering device, part of which is shown in cross-section. Fig. III is an end view of my automatic registering device. Fig. IV is a representation of my pendulum device for registering the approach of an in-coming train. Fig. V is a representation of a pliable attachment to be placed above the locomotive and the rear of the train for setting the pendulums into operation. 40 Fig. VI is a representation of my pendulum device for registering the departure of an out-going train from the block. Fig. VII is another view of the same, showing space left for locomotive attachment to pass through without affecting the same. Fig. VIII is a 45 representation of my device for alarming an approaching train of an open switch. Fig. IX is a section of switching still further illustrating the same.

Similar letters refer to similar parts throughout the several drawings.

50 1 is a section of the main line included between the dotted lines XX and YY. Let us suppose a train en-

tering from below going up the track. As the engine passes the dotted line YY the pliable attachment 11 situated above the cab of the locomotive strikes the pendulum 4 drawing it into the dotted position 13 60 and at the same time the pliable attachment takes a position similar to that shown in dotted outline 12. The motion is stopped by the stud 14, but at the same time the pendulum closes an electric circuit at 16 conveying current from metallic plug 15 to plug 17. From 65 plug 17 the current flows by wire 18 to plug 20. From plug 20 the current is conveyed by wire 25 around the electro-magnet 26, thence to plug 21, thence through wire 27 and storage battery or other source of power 28, it returns by wire 29 to metallic plug 15, thus completing the circuit. As the current passes around the electro-magnet 26, it magnetizes its iron core causing the iron shoe 30 to be lowered. Attached to this iron shoe is a steel extension 31 which is consequently lowered, compressing spring 61, and causing the ratchet 75 head 34 of the steel extension 31 to engage with one of the teeth of wheel 35 giving it a revolution equal to the space of one tooth and holding it from reverse motion by ratchet catch 36. The ratchet wheel 35 fits loosely upon the spindle 39, held in position by supports 38 80 and 84, and is insulated from it. Upon the same sleeve 40 is located a metallic disk 83 with a metallic brush 41 which makes an electric contact with disk 42 as soon as the brush 41 moves over the insulator 43, since the insulator 43 covers the distance of only one tooth of 85 35. As soon as the pendulum 4 swings to left thereby completing the exterior circuit through plugs 15 and 17 the disk 83 being rotated one tooth space becomes in electric contact with disk 42. Let us suppose the current starts at disk 42. Metallic sleeve 44 being in electric 90 communication with 42 the current is then conveyed by brushes to wire 45 and thence to plug 24 and wire 46 through the electric signals 47, these signals being of different colors depending upon whether they are on the right or left side of the moving train. Thence 95 the current is conveyed through storage battery or other source of power 48, and thence it returns by plug 19 and wire 49 through brushes to metallic sleeve 40, thence to disk 83 and brush 41 to disk 42, thereby completing the circuit. As soon as pendulum 4 swings 100 back the circuit through electro-magnet 26 is broken, hence the iron shoe 30 and steel extension 31 spring upward due to the elasticity of spring 61, the ratchet head 34 springs out and around the next tooth setting itself for the next train, the ratchet 36 keeping wheel 105 35 from returning to its previous position.

Suppose the train now advances up the track. As the caboose or rear of the train crosses the line XX, the pliable attachment similar to the one on the locomotive hits the pendulum 7 swinging it into the dotted 110 position 51 thereby closing a circuit at 50 between the plugs 53 and 52. From 52 the current goes through

storage battery 28 by wire 54, thence to plug 22 by wire 55, thence around electro-magnet 56 by wire 57 to plug 23, thence it returns to plug 53 by wire 58, thus completing the circuit. When the current encircles 5 electro-magnet 56, it causes its iron core to become magnetized, thus drawing the iron shoe 59 toward the iron core thereby compressing the spring 60 and by means of the ratchet head 32 engaging a tooth of wheel 33, it advances wheel 33 by one tooth, thus bringing 10 insulator 43 again under brush 41 and thereby opening the signal circuit. As soon as pendulum 7 swings to its natural position the circuit around electro-magnet 56 becomes broken, thus the iron shoe 59 springs back due to the elasticity of spring 60, until the head 62 15 limits its motion, the ratchet head 32 swinging out and over the next tooth due to the elasticity of the steel extension 37, thus setting itself for the next impulse, the ratchet 64 keeping wheel 33 from returning to its previous position.

20 Let us suppose now that two other trains have entered the block before the first train had left it. Wheel 35 would now be advanced three spaces ahead of the insulator 43. Hence not until the third train had left the block would the signal light or other indicating 25 device be turned out as each would advance the insulator 43 ahead one space and three advancements are required before wheel 33 catches up with wheel 35.

In a similar way a complete set of signals are given 30 coming down the track by a train entering from above in the opposite direction, and as the corresponding different lights or signals are made on its right and left a train already upon the block is notified of the approaching danger. Should all the trains upon a block going in the same direction be ordered to side-track, a 35 similar device will be located in the clear on the side track so that the caboose or rear of train closing the circuits consecutively upon my registering device will cause the danger signal to cease operating as soon as the main line is clear, thus the train coming from the 40 opposite direction having the right of way will have now no interfering signal and as a consequence will not have to stop. As the side-tracked train or trains again enter the main line the engine attachment will hit its corresponding turn-on pendulum and put the 45 danger signals on again.

5, 3 and 9, 8 are representations of pendulums for

preceding and following blocks of the main line, respectively, while 10 and 6 are for putting on and off signal when coming down block 1.

Let us suppose the train wishes to side-track. The 50 brakeman throws the switch lever 64 to the space 65 in order that the train may enter from the main line 66 to side track 67. The spring 68 being attached to lever 64 will draw rod 69 to right until block 71 attached to rod 69 touches abutment 70. Rod 69 being drawn to 55 right will force metallic bar 72 into the knife edges 75, thus forming a circuit as follows: Starting at knife edges 75 the current is conveyed through signals 80 by wire 79, thence through storage batteries or other source of power 78 by wire 81, thence to brush 82 insulated from frame 76, thence by rods 73 and 72 it returns to knife edges 75. If the switch is thrown to the left a similar danger signal is given. These devices are to be located at both ends of the main line switches and by giving different colored lights or signals, a train 60 and their crew are warned as to which end the switch is open.

Having thus described my invention, the following is what I claim as new therein and desire to secure by Letters Patent:

In a system of the class described, the combination with two sources of electrical supply, of a circuit connected with one of said sources, train actuated means for closing said circuit, an electro magnet in said circuit, parallel metallic disks, ratchet wheels carried thereby, one of said 75 disks being formed with a section of insulation flush with its periphery, the other of said disks being formed with a brush overlying the periphery of said first named disk, said disks being in circuit with the other source of electrical supply, signaling devices in said last named circuit, 80 an iron shoe adapted to be attracted by said electro magnet, a resilient rod projected fast through said shoe and having its upper end shaped as a pawl to engage one of said ratchet wheels, a compressible spring surrounding said rod, a second electrical circuit from said first named 85 source of supply, train actuated means for closing said second circuit, an electro magnet in said second circuit, a shoe adapted to be attracted thereby, a resilient rod projected fast through said shoe and having its upper end shaped as a pawl for engagement with the other of 90 said ratchet wheels and a compressible spring surrounding said last named rod.

WILLIAM HENRY HARRIS.
